UNITED STATES PATENT OFFICE.

EDWARD SACHS, OF DAYTON, OHIO, ASSIGNOR TO SACHS, PRUDEN & CO., OF SAME PLACE.

CAP FOR BOTTLE-STOPPERS.

SPECIFICATION forming part of Letters Patent No. 292,367, dated January 22, 1884.

Application filed December 14, 1883. (No model.)

To all whom it may concern:

Be it known that I, EDWARD SACHS, of Dayton, in the county of Montgomery and State of Ohio, have invented a new and Improved 5 Cap for Bottle-Stoppers, of which the following is a full, clear, and exact description.

This invention is designed with special reference to bottles in which the corks or stoppers are held in position by means of several 10 fine wires which are secured about the neck of the bottle, and then twisted or otherwise suitably fastened over the top of the cork itself, for the purpose of preventing the stopper or cork being forced out from its place 15 by the gas within the bottle. Experience has demonstrated the fact that where fine wire is used—such, for instance, as that employed by Sachs, Pruden & Co., of Dayton, Ohio, in bottling their ginger-ale—the gas within the bottle 20 has forced the stopper out a slight distance above or beyond the rim of the neck of the bottle, thereby causing the fine-wire fastener to become considerably embedded in the cork. In view of the wire cutting into or becoming 25 embedded in the cork, it becomes a very difficult operation to readily and easily release its hold upon the cork. There is also much time employed and trouble occasioned in removing or drawing the stopper or cork from bottles of 30 the class above specified, owing to the fact that the corkscrew very often finds its way either to one side or the other of the cork, when, to do its work effectively and to obtain a firm hold, it should be screwed into the 35 cork directly in its center.

The object of this invention is to overcome these objections, and to furnish a neat, cheaply-manufactured, and durable cap, which is easily and readily applied to bottles, and at the 40 same time may be stamped with any design or inscription the manufacturer or user may see fit.

The nature of my invention and the manner in which the same is or may be carried 45 into effect will be readily understood by reference to the accompanying drawings, in which I have represented the device in plan in Figure 1, and the same as applied to a bottle in Fig. 2. Fig. 3 is a horizontal section on line 3 3, Fig. 2.

In the cap A—which may be made of metal

or any other suitable material—is formed a perforation, B, directly or nearly in its center. The cap A, which is of a round disk-like shape, is, after the bottle is properly 55 corked, placed over the cork. It is slightly larger in circumference than the mouth of the bottle, and is so shaped as to fit neatly and snugly above it. Two wires, C C", are twisted about one another in such manner as to fit 60 closely around the neck of the bottle. The four ends of the wires are so entwined around each other as to form in effect three wires, which are brought upward and twisted over the cap A, as is well known by those skilled 65 in the art of corking bottles, thereby securely fastening the same in position.

It will thus be seen that by using my improved cap there is no longer any liability of the wires becoming embedded in the cork, even 70 should it be forced by the gas within the bottle a slight distance from its proper position.

When it is desired to remove the cork from the bottle, the corkscrew is put into the central perforation in the cap A—which serves as 75 a guide therefor—and is then screwed into the cork a sufficient distance to give it a firm hold thereon. The wires are then bent away from about the cap, and the cork, with the cap, is removed from the bottle, when the contents are 80 ready to be poured out.

I would state in conclusion that the caps may be used over and over again so long as they retain proper shape.

Having thus fully described my invention, 85 what I claim as new, and desire to secure by Letters Patent, is—

1. A cap for bottle-stoppers, made of metal or other suitable material, provided with a central perforation, for the purposes hereinbefore described. 90

2. The combination of the bottle with the centrally-perforated metallic cap a, stopper, and holding-wires, substantially as and for the purposes hereinbefore set forth. 95

In testimony whereof I have hereunto set my hand, this 12th day of December, 1883, in the presence of two subscribing witnesses.

EDWARD SACHS.
